Primary Examiner—Susan Bennett Hattan

(57) **CLAIM**

I claim an ornamental design for a sprayer shroud, as shown and described.

DESCRIPTION

FIG. 1 is a front perspective view of a sprayer shroud showing my new design;

FIG. 2 is a rear perspective view of the sprayer shroud shown in FIG. 1;

FIG. 3 is a side view of the sprayer shroud shown in FIG. 1;

FIG. 4 is a side view of the sprayer shroud shown in FIG. 1;

FIG. 5 is a front view of the sprayer shroud shown in FIG. 1;

FIG. 6 is a rear view of the sprayer shroud shown in FIG. 1;

FIG. 7 is a top view of a sprayer shroud shown in FIG. 1; and,

FIG. 8 is a perspective view of a sprayer shroud shown in FIG. 1 attached to a bottle.

The broken line representations in FIGS. 1 through 8 are depicts environmental subject only and form no part of the claimed design.

1 Claim, 4 Drawing Sheets

FIG. 1
